WINDOW REGULATING MEANS

John B. Parsons, Toledo, Ohio

Application April 25, 1939, Serial No. 270,015

8 Claims. (Cl. 180—1)

This invention relates to an automotive vehicle window regulating system, and is particularly directed to automatic means for controlling the windows of such vehicles.

An object of the present invention is to utilize the starting motor of the vehicle as a power source for driving fluid power means for opening and closing the windows, controllable by means located within easy access of the operator, or other occupant, of the vehicle.

Another object is to utilize a starting motor provided with the so-called "Bendix drive" for operating fluid pump means associated therewith to actuate means coupled to the windows for moving the latter, means being provided to render the starting motor effective to perform the dual operations of driving the fluid pump and cranking the vehicle engine.

A further object is to provide the starting motor with a novel remotely controlled starter drive of this type adapted to be selectively latched or unlatched to permit the starting motor to be used to drive a fluid pump to operate the windows or to crank the engine, or both.

Further objects of the invention will appear as the description proceeds in connection with the accompanying drawing, in which:

Figure 1 is a diagrammatic view of an embodiment of the present invention, only one of the plurality of windows to be operated being illustrated; and

Figure 2 is an enlarged fragmentary sectional view of the starter drive and associated mechanisms illustrating details of the present invention.

Figure 1 illustrates somewhat fragmentarily a portion of an automobile indicated generally at 10, and shown as including a dash board 14, floor 15 and toe board 16. One of the doors 18 of the vehicle is shown as including a window opening 19 adapted to be closed by means of a glass or other transparency 20. Mounted interiorly of the door 18 and below the glass 20 is the window operating means indicated generally at 22, and including a pair of levers 23 and 24 pivotally connected intermediate their ends, and each having one end pivoted respectively to a glass supporting channel 25 and a support 26 carried by the door. Lever 23 is connected by a rod or link 28 for operation by a power unit, indicated generally at 30. The power unit per se forms no part of the present invention, but is included in the subject matter of a co-pending application of John B. Parsons and Burton S. Floraday, Serial No. 275,207, filed May 23, 1939.

The power unit 30 comprises a reciprocable

cylinder 31 connected to the lower end of link 28, and within which is positioned solenoid controlled fluid actuated means to raise and lower the cylinder 31 and thus the window 20 through the rod 28 and associated linkage. Fluid is supplied to and withdrawn from the cylinder through a conduit 32 connected to a supply pipe 33 leading from a suitable pump 35.

As diagrammatically illustrated in Figure 1, 10 means are shown for supplying power to the cylinder 31, as are means for controlling the supply means, and means remote therefrom for energizing or rendering effective the entire system. The power means has been shown as a 15 hydraulic system including a reservoir 37 which need not be a separate reservoir, as the use of the vehicle's brake-system reservoir or the crank case of the engine is contemplated as a source of fluid or oil for the present system.

20 A pump 35 of desired characteristics is an essential element of the present invention, and, although the type of fluid pump used is immaterial, the means for operating such a pump forms an important part of this invention. The pump 35 is, therefore, illustrated as directly associated with a conventional starting motor 40, and as provided with a fluid supply duct 41 in communication with the reservoir 37, and the pipe or conduit 33, suitably branched into any desired 25 number of branches, herein illustrated as four pipes 43, 44, 45 and 46, each of which is connected to a power unit coupled to and capable of operating a window of the vehicle. As illustrated, the pipe 43 leads to conduit 32 and thus to the unit 30, associated with window 20 in the door 18, and it will be understood that the other pipes lead to similar units associated with three other windows of the vehicle (not shown).

30 A valve, indicated at 48, is associated with 40 and may form a part of the pump 35 for the purpose of controlling the fluid flow during operation of the latter. This valve is preferably actuated by means of a solenoid coil 50 connected into an electrical circuit later described.

45 The starting motor 40 serves to crank the engine of the vehicle as well as drive the pump 35, and is thus provided with a starter drive assembly indicated generally at 52 and shown in detail in Figure 2. Motor 40 includes an armature 53 having a shaft 54, one end of which is supported in a suitable bearing 55. The shaft 54 is provided with an extension 56, the outer end of which is supported in a bearing 57 carried by a housing 58, which partially encloses the drive mechanism. The drive mechanism is of

the type wherein a pinion gear 60 is rotatable with and with respect to the shaft extension 56, as well as being movable longitudinally thereof into engagement with a flywheel or other gear 62 of the engine. Pinion 60 is internally threaded at 63 for threaded engagement with a sleeve 64 fixed against longitudinal movement on the armature shaft and having limited rotary movement with respect thereto through the medium of a starter spring 65 having one end secured to the sleeve 64 and the other end secured to a collar 67 pinned or otherwise fixed to the shaft 54.

Operation of the starter drive thus far described is in accordance with well known practice. However, in order to adapt the starting motor for use in operating the pump 35 independently of its use to crank the engine, latch or lock means are provided to restrain enmeshment of the pinion 60 with the gear 62 under certain conditions. Such means preferably comprises a longitudinally movable pin 69 located in a bore 70 in the extension 56 and normally urged outwardly by means of a spring 71 interposed between the inner end of the pin 69 and the end of bore 70. Pin 69 is formed with an intermediate reduced portion 72 located so that inward movement of pin 69 permits a ball 74 to drop downwardly out of the path of the pinion 60. The ball 74 is normally disposed in a transverse bore 75 in the extension 56 and has a portion engaging a shoulder 77 on the pinion 60, thereby holding the pinion against longitudinal movement.

A lever 80 suitably pivoted to the bell housing 81 of the engine is adapted to be rocked into engagement with the outer end of pin 69 to release the pinion 60. The lever 80 may be remotely controlled from the dash 14, or other convenient part of the vehicle, by a Bowden wire 83 supported in a suitable sheath 84 and having a control button 85 at one end thereof. The lever 80 is also arranged to close a switch 87 mounted in the path of the lever. Switch 87 comprises spaced contacts 88, 89 and 91 adapted to be bridged by a contact bar 90 movable into engagement therewith in response to rocking movement of lever 80. The arrangement is such that pinion 60 is released prior to the closing of switch 87 by the lever 80. Thus it will be noted that the motor 40 is capable of being energized by means of the switch 87, which is connected into an electrical circuit now to be described.

Referring again to Figure 1, the circuit illustrated includes the starting motor energizing circuit, including an electro-responsive switch, as well as a circuit to a starting motor control switch so that the motor may be simultaneously or conjointly operated for window actuation and starting the engine, or each operation may be independently performed. Associated with the starter motor 40 is a solenoid actuated switch indicated at 92.

The switch 92 includes a pair of contacts 93 and 94, which may be closed electrically by energization of a solenoid coil indicated by the reference numeral 95 and which moves a plunger carried contact bar 96 to bridge the contacts. Energization of the solenoid causes current to flow to the starting motor to energize the same and drive the pump 35. Obviously, if the motor 40 is to be used to supply power to operate the windows of the vehicle, additional means are required to energize the motor so that the driving connection between the starter drive and the engine flywheel will not be established at times when it is desired to regulate the windows.

In accordance with standard automotive practice, a single wire system is used to control the organization of the present invention, all circuits leading from a battery 98 to a suitable ground. A switch 100 is mounted for convenient manipulation by the operator of the vehicle as on the dash 14, and may be of any suitable construction, preferably provided with four spaced contacts or binding posts to which certain of the wires of the present circuit are connected. The switch mechanism may be enclosed in a suitable box within which are carried a plurality of independently operable elements 101 for controlling respectively each of the windows of the vehicle. 5 Each of the switch elements is preferably arranged so that it has a neutral position from which the switch is moved upwardly to energize a circuit to close the window and downwardly to energize a circuit to open the window. Thus 10 20 the element 101 is arranged to interconnect a plurality of contact elements 102, 103, 104 and 105, which are connected into the circuit in the following manner. Contact 102 is connected by a lead 106 to one side of the solenoid coil 95, the other side of the solenoid being connected by lead 107 to a suitable ground. Contact 103 is connected to one side of the solenoid coil in unit 30 by a lead 109, it being noted that four leads, one for each window power unit, are illustrated as 25 being connected to the contact 103, which is preferably a four-part contact or four separate contacts. The circuit is completed by suitably grounding the other end of the coil. Contact 104 is connected to a switch 110 in turn connected to the battery 98 by means of a lead 111. Switch 110 may, if desired, be a conventional ignition or accessory switch of the vehicle, or a combined ignition and accessory switch. Contact 105 is 30 connected by a lead 113 to one side of the coil 50 mounted on the flow control valve 48, which coil is grounded at 114.

From the description thus far, it is to be noted that the electrical circuit is energizable to operate the motor 40 through switch 92. Accordingly, by manipulating switch element 101 preferably in an upward direction, the window may be closed in the following manner. Element 101 is 45 preferably adapted to bridge contacts 102, 103 and 104 when in its uppermost position, and when such contacts are thus connected current will flow from battery 98 through lead 111, switch 110, switch 100, lead 106 and to solenoid coil 95 to energize the solenoid and close switch 92, and thus energize motor 40. At the same time the solenoid in the unit 30 is energized through lead 109, which is connected to the battery upon manipulation of element 101. Unit 30 is arranged so that fluid will pass into or out of the cylinder 31 when its solenoid is energized. Valve 60 48 is arranged to permit fluid to be pumped out of the unit 30 when solenoid 50 is energized and into unit 30 when the solenoid is not energized. Thus, in this instance the coil 50 is not connected onto the circuit and not energized, so that fluid 65 will be pumped into unit 30, and thus urge the window toward closed position.

When it is desired to open the window, switch element 101 is moved downwardly, in which position all four contacts 102, 103, 104 and 105 are bridged and lead 113 is additionally supplied with current to energize the solenoid 50 to move valve 48 into position to permit pump 35 to withdraw fluid from the unit 30 and thus lower or open the window. The foregoing describes the 70 operation when the motor 40 is energized and

the plunger 69 is in its outer position to latch the pinion to the shaft extension 56 and thus prevent the starter from cranking the engine.

To use motor 40 as a starting motor, either independently of or concurrently with the operation of the window regulating mechanism, the motor is energized upon closing of switch 87. Contact 88 is connected to the battery 83 by means of a lead 115, while contact 91 is connected to one side of the solenoid coil 95 by a lead 117. Thus, closing the switch 87 energizes the solenoid 95 to close the motor circuit to energize the motor 40. At the same time, contact 89 receives energy from the battery, which is conducted through a lead 116 to one side of the flow control valve solenoid 50 to energize the latter. By rocking lever 80 toward the switch 87, by means of button 85 on wire 83, the pinion 60 is first unlatched and then the contacts 88, 89 and 91 bridged by the bar 90 to energize the motor 40, through the medium of solenoid 95. At the same time, solenoid 50 is energized to move the valve 48 into position to lower the window. Thus it will be noted that irrespective of the position of switch element 101, should it be desired to operate the window, such operation is temporarily interrupted if it is desired to close the window during the period in which the motor is cranking the engine, as solenoid 50 is always energized upon energization of motor through the medium of switch 87.

From the foregoing description it will be apparent that means are provided for utilizing a single power source for the dual purpose of operating the vehicle windows as well as cranking the engine, means also being provided for preventing actuation of a normally automatic starter drive when it is desired to utilize the starting motor only to operate the window regulating means. It will also be noted that the arrangement is such that should the window control switch be actuated to close the window and the starter switch be concurrently actuated, the window operating means is temporarily rendered ineffective to close the window until the manual switch 87 is opened, coil 50 deenergized and valve 48 positioned to permit fluid to be pumped to the unit 30. On the other hand, should it be desired to open the window concurrently with the cranking of the engine, the coil 50 is energized by either of the switches 87 or 100 to position the valve 48 to permit fluid to be pumped out of unit 30.

It will be understood that changes in details of construction, arrangement and operation may be effected without departing from the spirit of the invention, especially as defined in the appended claims.

What I claim is:

1. A regulating system for a vehicle having an engine and including a movable vehicle part, fluid actuated means connected to move said part, a motor, a drive mechanism for cranking the engine coupled to said motor, a pump driven by said motor for supplying fluid to said fluid means, electro-responsive means to energize said motor to drive said pump, mechanically operated means to cause said electro-responsive means to energize said motor to crank the engine, and a releasable locking element to render said drive mechanism ineffective during the energization of said motor by said electro-responsive means to drive said fluid pump alone.

2. A window regulating system for a vehicle having an engine and including a movable window, fluid actuated means connected to move

5 said window, a motor, a drive mechanism for cranking the engine coupled to said motor, a motor driven pump for supplying fluid to said fluid means, a solenoid actuated switch for energizing said motor to drive said pump, a manually actuated switch for energizing said motor to crank the engine, blocking means engageable with said drive mechanism to render said drive mechanism ineffective, and means for releasing 10 said blocking means.

3. A vehicle window regulating system including a movable window, fluid actuated means connected to move said window, a motor driven pump for supplying fluid to said fluid means, electro-responsive means for energizing said motor to drive said pump, said motor being operable to crank the engine of the vehicle, mechanical blocking means to prevent cranking of the engine, combined mechanical and electrical means to render said last means ineffective and to energize said motor, and a common control for said combined means.

4. A vehicle window regulating system including a movable window, fluid actuated means connected to move said window, a motor, a pump for supplying fluid to said fluid means, electro-responsive means for energizing said motor to drive said pump, a drive mechanism, said motor being operable to crank the engine of the vehicle through said drive mechanism, releasable locking means associated with said drive mechanism to render said drive mechanism ineffective, combined mechanical and electrical means to release said locking means and energize said motor, and a common control for said combined means to energize said motor through said electro-responsive means.

5. The combination with a vehicle having an engine, a motor operable to crank the engine, a window in the vehicle, fluid operated means for controlling the window, and a pump associated with said motor for actuating said fluid means, of a starter drive coupled to said motor, releasable means for locking said starter drive in ineffective position, means for releasing said last means and for energizing said motor to crank the engine, and a solenoid for energizing said motor to drive said pump independently of said releasing means.

6. The combination with a vehicle having an engine, a motor operable to crank the engine, a window in the vehicle, and fluid operated means for controlling the window, of a starter drive associated with the motor, releasable means for blocking operation of said starter drive, manual means for releasing said releasable means and energizing said motor to crank the engine, and a solenoid for energizing said motor to operate said fluid means to operate the window independently of said releasing means.

7. The combination with a vehicle having an engine, a motor operable to crank the engine, a window in the vehicle, and operating linkage for controlling the window, of a fluid pump associated with said motor, power means coupled to said pump for moving said linkage, a starter drive coupled to said motor, means to block the operation of said starter drive, means for releasing said blocking means and for energizing said motor to crank the engine, and said last means including electro-responsive means to energize said motor to operate said pump when said starter drive is blocked.

8. The combination with a vehicle having an engine, a motor operable to crank the engine, a window in the vehicle, and operating linkage for

controlling the window, of a fluid pump associated with said motor, power means coupled to said pump for moving said linkage, a starter drive coupled to said motor and adapted to engage a member of the engine to crank the latter, releasable means to block engagement of said starter drive with said engine member, means for re-

leasing said blocking means and energizing said motor to crank the engine, and said last means including electro-responsive means to render said motor effective to operate said pump when said starter drive is blocked.
